SAFETY INTERLOCK SWITCH

David Satinoff, Utica, N. Y., assignor to the United States of America as represented by the Secretary of the United States Air Force

Application May 14, 1951, Serial No. 226,259

6 Claims. (Cl. 200—50)

(Granted under Title 35, U. S. Code (1952),
sec. 266)

1

The invention described herein may be manufactured and used by or for the Government for governmental purposes without payment to me of any royalty thereon.

This invention relates to electrical switching devices and particularly to switches of the safety interlock type.

In cabinets or other enclosures for electrical equipment operating at dangerously high voltages, such, for example, as radio transmitters, it is customary as a safety precaution to provide interlock switches on all doors for the purpose of automatically deenergizing the equipment when a door is opened. Frequently switches of this type employ spring pressure to open the switch. In such switches the contacts may freeze in their closed position, due to corrosion or moisture and cold, causing the switch to remain closed when the door is opened and thus fail as a safety device. It is an object of this invention to provide a two-piece interlock switch which can under no circumstances remain closed when the door is opened.

It is sometimes necessary to make tests or repairs on equipment when in an energized condition. In such cases the safety interlock is frequently nullified by wedging the switch in a closed position or installing a jumper across the switch. The danger in this is that such makeshift "cheating" devices may thoughtlessly be left in place thus defeating the purpose of the safety interlock. It is accordingly another object of this invention to provide a two-piece safety interlock switch having a built-in "cheater" which can only be operated intentionally and which, if operated, is automatically rendered inoperative the next time the door is closed.

The structural details of an interlock switch incorporating the above features are shown in the accompanying drawings in which:

Fig. 1 shows a sectional plan view of the interlock switch in closed position;

Fig. 2 shows a sectional elevation of the switch with plug and receptacle parts of the switch separated;

Fig. 3 shows a sectional plan view of the receptacle part of the switch with the "cheater" in operative position; and

Fig. 4 is an isometric view of the assembled switch.

Referring to the drawings, the switch is composed of mating plug and receptacle parts generally indicated by the numerals 1 and 2, respectively. The plug 1 has a body 3 of insulating material, and molded therein are two internally

2

connected contact prongs 5 and 6. The insulating body of the plug is fastened to a metallic backing plate 7 by rivets 8 and 9.

The receptacle part 2 of the switch consists of a body of insulating material having upper and lower halves 10 and 11 fastened together and to a metallic angle plate 12 by rivets 13 and 14. The two halves 10 and 11 of the receptacle body may be, as in the embodiment shown, identical moldings having recesses therein to receive and position the conductors 15 and 16 and the spring contacts 17—18 and 19—20 which are fastened to the ends thereof by any suitable conductive fastenings such as spot welds, etc. Terminals 21 and 22 are provided at the outer ends of conductors 15 and 16 for connecting the switch into an electric circuit.

When the switch is in its closed position, as shown in Fig. 1, the contacts 5 and 6 bridge the gap between contacts 17 and 19 and thereby complete a circuit between terminals 21 and 22. In the open position of the switch, shown in Fig. 2, the plug is removed from the receptacle and the circuit between terminals 21 and 22 is broken. The plates 7 and 12 provide means for mounting the switch. In a typical use of the switch the receptacle part 2 would be mounted on the chassis of a cabinet enclosing electrical equipment while the plug part 1 would be mounted on a door to the cabinet. Since opening the door removes the plug part from the receptacle part of the switch, failure of the switch to operate when the door is opened is impossible.

In order to permit intentional completion of the circuit between terminals 1 and 2 when the plug and receptacle parts of the switch are separated, the receptacle part has built into it what may be termed a "cheater." This device consists of a plunger 23 having a plate 24 attached to its inner end and carrying connected spring contacts 25 and 26. The plunger is positioned and guided at its outer end by a passageway 29 formed in the two halves of the receptacle body, and at its inner end by plate 24 which engages and slides in slots 27 and 28 in the upper and lower halves 10 and 11, respectively, of the receptacle body. The length of the plunger is such that in its innermost position its outer end protrudes a short way from the receptacle body as shown in Figs. 1 and 2. The plug is provided with a recess 30 to receive the protruding end of the plunger when the switch is in its closed position. In order to latch the plunger 23 in its innermost position, which is the inoperative position of the "cheater," the plunger is provided with a notch

31 which engages the edge of the opening in plate 12 through which the plunger 23 passes. The spring finger 32 urges the plunger against this edge of the opening at all times causing the notch and edge to become engaged when the two come into alignment.

When the switch is in the open position, the "cheater" may be operated by pressing the plunger against spring 32 to disengage the notch 31 and then pulling the plunger all the way out to engage contacts 25-26 with contacts 18-20, thus completing a circuit between terminals 21 and 22. The "cheater" may be manually disengaged at any time by pushing the plunger all the way in so that the connection between contacts 18-20 and 25-26 is broken and the shoulder of notch 31 drops in behind plate 12 under the influence of spring 32. However, should the "cheater" be left in its operative position, it will be automatically forced to its latched inoperative position by the body 3 of plug 1 the next time the interlock switch is closed. It will then remain in its inoperative position until intentionally operated in the manner above described. Reopening of the interlock switch will not operate the "cheater" even if the plunger should stick to or become frozen to the plug body 3, since the restraining action of the shoulder of notch 31 against the plate 12 would either cause the plunger to break away from the plug or else cause the plunger itself to break.

I claim:

1. A safety interlock switch having two separable mating parts, said switch being closed by joining said parts and opened by separating said parts, means attached to one of said parts and manually operable when said switch is open to form an electrical by-pass around said switch, and means attached to the other part of said switch and cooperating with said manually operable means when said switch is closed to remove said electrical by-pass.

2. A safety interlock switch comprising separable mating plug and receptacle parts, said receptacle part having a pair of contacts and a pair of terminals connected to said contacts for connecting said switch into an electric circuit, said plug part having a pair of contacts electrically connected together and positioned so as to engage the contacts of said receptacle part and to form an electrical connection therebetween when the switch is in its closed position with plug and receptacle parts joined, a second pair of contacts located in said receptacle part and connected to said terminals, a pair of electrically connected movable contacts in said receptacle part, manual actuating means for moving said pair of movable contacts between an inoperative position and an operative position, said pair of movable contacts in said operative position engaging said second pair of contacts and forming an electrical connection therebetween, and means operated by closing said switch to force said movable contacts from said operative position to said inoperative position.

3. A safety interlock switch comprising separable mating plug and receptacle parts, a pair of terminals associated with said receptacle part for connecting said switch into an electrical circuit, said switch providing a connection between said terminals in its closed position when

5 said plug and receptacle parts are joined and an open circuit between said terminals in its open position when said plug and receptacle parts are separated, an auxiliary switch in said receptacle part for providing a connection between said terminals, a plunger connected to said auxiliary switch and protruding from said receptacle part to permit manual operation of said auxiliary switch by pulling said plunger outward from said receptacle part, said plunger protruding from said receptacle part at a point normally covered by said plug when said plug and receptacle parts are joined, whereby, if said auxiliary switch is in its operative position, the action of said plug part against said plunger pushes said auxiliary switch to an inoperative position during closure of said interlock switch.

4. A safety interlock switch for mounting on the door of a cabinet containing electrical equipment for the purpose of closing the energizing circuit of said equipment when said door is closed and opening the energizing circuit of said equipment when said door is opened, an auxiliary switch in said interlock switch and connected in parallel thereto, means accessible when said door is open for manually closing said auxiliary switch, and means on said door cooperating with said manual closing means for opening said auxiliary switch when said door is closed.

5. A safety interlock switch comprising separable mating plug and receptacle parts; said receptacle part having two pairs of separated contacts connected in parallel between two external terminals for connecting the switch into an electric circuit; said plug part having a pair of contacts electrically connected together and positioned so as to engage one pair of contacts of said receptacle part and to form an electrical connection therebetween when the switch is in its closed position with plug and receptacle parts joined; a pair of electrically connected movable contacts in said receptacle part; plunger means connected to said movable contacts and, when said movable contacts are in an inoperative position, protruding a short way from said receptacle part at a point normally covered by said plug part when said switch is closed, whereby, when said switch is open, said movable contacts may be brought into an operative position in engagement with and bridging said other pair of contacts by manually pulling said plunger outward from said receptacle part, and whereby said plug part acts against said plunger to return said movable contacts to an inoperative position when said switch is closed.

6. Apparatus as claimed in claim 5 in which spring actuated latching means are provided to prohibit movement of said plunger from its innermost position unless said means is manually unlatched.
